CHARLES W. FERREIRA.

By *Arthur H. Sloc*.

ATTY.

UNITED STATES PATENT OFFICE

CHARLES E. FERREIRA, OF OAKLAND, CALIFORNIA

RECLINING CHAIR

Application filed November 26, 1928. Serial No. 321,910.

My invention relates to improvements in reclining chairs wherein a pivoted back is normally held in substantially upright position and arranged to be swung rearwardly to a reclining position by the weight of an occupant of the chair when desired.

The present invention is an improvement upon the device disclosed in my co-pending application, Serial Number 145,805 filed November 2, 1926 and consists of improved features of construction and arrangement adapted to provide a more efficient chair.

The primary object of the present invention is to provide an improved reclining chair.

Another object is to provide an improved construction which is simple and positive in its action and in which the operating parts are so constructed and arranged as to avoid any possible injury to an occupant or damage to his apparel.

A further object is to provide an improved construction whereby normally the back is positively held in a normal upright position, and which will facilitate the movement of the back of a desired reclining position.

Another object is to provide an improved construction having a positive manually operated actuating means.

A still further object is to provide an improved construction in which the parts are simple and rugged and which cannot ordinarily get out of order.

I accomplish these and other objects by means of the improved device disclosed in the drawings forming a part of the present application wherein like characters of reference are used to designate similar parts throughout the drawings and specification and in which—

Fig. 1 is a transverse section showing the inner side of one of the side frame members, the seat and upholstery of the back being indicated in dotted lines;

Fig. 2 is a broken side elevation, partly in section of the back retaining means and indicating the manner in which the same is moved to release the back;

Fig. 3 is a horizontal section of the chair

frame showing in plan the arrangement of the back retaining means;

Fig. 4 is a broken vertical section of the chair frame showing a front elevation of the retaining means; and

Fig. 5 is a front elevation of a detent member.

Referring to the drawings, the numeral 1 is used to designate a pair of side frame members each having leg portions 2 and an upwardly extending arm portion 3. A back 4 is pivotally mounted as at 5 between the frame members 1, said back comprising a suitable frame upon which is applied suitable upholstery 4' and provided with downwardly disposed extensions 6 at each side of the frame. The extensions 6 are arranged adjacent the inner sides of the frame members 1 and are formed at an angle to the back 4 such that when the extensions are moved to a normal position against flanges 7 formed upon the inner sides of the rearward leg portions 2, the back will then be held in its normal upright position as shown in Fig. 1 of the drawings.

A pair of ratchet bars 8 are pivotally connected to the lower ends of the extensions 6, said bars being arranged to extend forwardly along the sides of the frame members 1 past detent members 9 secured upon the inner sides of the frame members 1. The detent members 9 each consist of a hollow body portion having a slot 11 arranged to receive a bar 8, the lower portion of said body being shaped to form a detent 12 arranged to engage any of a plurality of ratchet teeth 13 formed upon the bar 8. The teeth 13 are formed upon the lower edge of the bars 8 in downwardly disposed and forwardly faced position. The bars 8 are normally held by gravity in engagement with the detents 12. However, springs 14 are mounted within the upper hollow portion of the body portions 11 to insure a positive engagement of the bars with the detents, and to prevent rattling.

The forward ends of the bars 8 extend past the detent members. Arms 16 are pivotally mounted adjacent the detent members 9 and arranged to engage the ends of the bars 8, said arms preferably having rollers 17.

mounted thereon to form rolling contact with the under side of the ends of the bars 8 as shown in Figs. 1 and 2, the arms are preferably secured upon a shaft 18 extending between the side frame members 1 and supported upon suitable bearings formed upon the detent members 9. A lever 19 is mounted in connection with the shaft 18 for actuating the same, said lever preferably being formed integrally with one of the arms 16 in the form of a bell crank. The lever 19 extends upwardly adjacent the inner side of one of the side frame members 1 and is provided with a slightly offset handle portion 21 adapted to provide a hand hold whereby the lever may be shifted to actuate the shaft 19 and arms 16. A guide 22 is secured upon the member 1 to limit the movement of the lever 19.

10 20 The detent member is provided with a rearward disposed extension 23 arranged to slidably engage a rod 24 extending through said extension and connected to an extension 26 carried by the extensions 6 of the back. 25 Springs 27 are mounted upon the rods 24 and arranged to be compressed between the extensions 23 and 26 to exert a pressure operating to normally move the back to its normal upright position.

30 35 The detent member 9 is also provided with an extension 28 formed upon its lower end and arranged to form a support for a cross member 30 connecting opposite side frame members 1. A second cross member 31 is secured between the members 1 adjacent the front of the chair, said cross members 29 and 31 forming supports upon which a suitable upholstered seat 32 is supported.

40 45 In operation, the back 4 is normally held in substantially upright position by the springs 27, the normal position being defined by the engagement of the extensions 6 with the flanges 7. The ratchet teeth 13 are so positioned that the face of the front tooth 13 of each bar 8 will be received in back of the detents 12 to normally prevent the back from being swung rearwardly from its normal position. The ratchet bars 8 are normally held in operative engagement with the detents by 50 gravity, and the springs 14 prevent inadvertent disengagement and prevent rattling of the bars within the detent members.

55 60 When it is desired to move the back to a reclining position, the occupant of the chair moves the lever 19 rearwardly, thereby swinging the arms 16 upwardly and lifting the ratchet bars 8 out of engagement with the detents 12 as indicated in dotted lines in Fig. 2. As the occupant now rests his weight 65 against the back 4, said back is swung rearwardly upon its pivot mounting 5 against the pressure of the springs 27, said spring being compressed as the extension 6 is moved forwardly. When the back has been moved to the desired reclining position, the lever 19

is released and the ratchet bar 8 permitted to reengage the detent, one of the more rearwardly disposed teeth of each bar 8 then engaging the detent to prevent further rearward movement of the back. The back will remain in the reclining position so long as the weight of the occupant is supported thereon. When the occupant removes his weight from the back of the seat, the springs 27 operate to return the seat back to normal position, the ratchet teeth 13 and the detent 12 being provided with inclined surfaces 33 and 34 respectively whereby the back may be moved freely rearwardly past the detent. The ratchet bars 8 are provided with ribs 36 formed upon the sides thereof to engage the sides of the detent member 9 and thereby limit the forward movement of the back bars through the slots 11 and thus limit the rearward inclining of the seat back.

70 75 80 85 My improved chair is designed primarily for installation upon automobile busses and stages. In this connection, my improved chair construction is particularly advantageous as there are no outwardly protruding parts which might cause injury to occupants or damage to their apparel or luggage, and the entire structure is compact and easily operated. The chair is of course not restricted to this particular purpose, but is useful for many other purposes.

90 95 Having thus described my invention what I claim as new and desire to secure by Letters Patent is—

100 105 110 115 120 125 130 1. A reclining chair comprising a pair of side frame members; a stationary seat; a back pivotally mounted between said side frame members for adjustment relative to the seat and having extensions projecting downwardly from the pivot points of said back; toothed bars each pivotally connected at its rearward end to the adjacent extension and movable longitudinally along the side frame members by a pivotal movement of the back; guide members secured upon the side frame members and slidably engaging the forward ends of the bars, said members being provided with detents adapted to be engaged by the teeth of the bar to normally prevent forward longitudinal movement of the bars and thereby prevent rearward pivotal movement of the back; means normally holding the bars with teeth thereof in engagement with the detents; a shaft mounted upon the side frame members and extending therebetween; bar actuating arms secured upon the shaft adjacent the bars and movable to engage said bars; a hand lever secured upon the shaft and movable to manually move the arms simultaneously to disengage the bars from the detents to permit movement of the back and bars to desired positions, said lever extending upwardly in proximate relation to a side frame member for operation by an occupant seated in the chair in normal sitting

- position; a spring guide rod mounted in connection with the back extension and the guide member; and a compression spring mounted upon said rod and compressed therebetween, 5 said springs normally pressing the extensions rearwardly to move the back to a normal upright position.
2. In a reclining chair the combination with a seat and a pivoted back movable to reclining positions relative to the seat by the weight of an occupant imposed upon the back, of a control mechanism comprising a toothed bar pivotally connected at its rearward end to the back and longitudinally movable by a pivotal movement of said back; a guide member secured adjacent the seat and slidably engaging the forward end of the bar and provided with a fixed detent adapted to be engaged by the teeth of said bar to hold the bar against longitudinal movement and thereby secure the back against pivotal movement; an actuating arm pivotally mounted adjacent the bar and movable to engage and pivotally move the bar out 10 of engagement with the detent; a hand lever pivotally mounted adjacent the seat and connected to the actuating arm for manually moving the bar to releasing position, said lever extending upwardly at one side of the seat for operation by an occupant seated in the chair in normal sitting position; a spring guide rod connected to the back and to the guide member in spaced relation to the tooth bar; and a compression spring mounted upon 15 said rod and compressible by a rearward movement of the back to a reclining position to return said back to normal upright position when relieved from the weight of an occupant.
3. In a reclining chair having a seat and a pivoted back movable to reclining positions relative to the seat by the weight of an occupant imposed upon the back, of control mechanism comprising a tooth bar pivotally connected to the back at each side of the seat and longitudinally movable relative to the seat by a pivotal movement of said back; a pair of guide members secured at the sides of the seat and slidably engaging the forward ends 20 of the bars, said members being provided with tooth engaging detents adapted to engage the bars and hold the same against longitudinal movement and thereby secure the back against pivotal movement; a shaft mounted transversely of the chair below the seat; bar actuating arms secured upon the shaft and movable therewith to engage the forward ends of the bars; and a hand lever secured upon the shaft at one side of the seat for manually moving the shaft and arms to bar releasing position, said lever extending upwardly at one side of the seat for operation by an occupant seated in the chair in normal sitting position.
4. In a reclining chair the combination 25 with a seat and a pivoted back movable to reclining positions relative to the seat by the weight of an occupant imposed upon the back, of securing means for normally holding the back against rearward pivotal movement and normally permitting free forward movement of said back, said means being operable to release the back for rearward movement thereof to a desired reclining position; a spring guide rod connected at one end to the back independently of the securing means; a stationary guide mounted upon the chair and engaging the opposite end of the rod; and a compression spring mounted upon the rod, 30 said spring being compressed against the guide by a rearward movement of the back to a reclining position to automatically return said back to normal upright position when relieved from the weight of an occupant.
5. A control mechanism for reclining chairs comprising a pair of toothed bars mounted in spaced parallel relation at opposite sides of a chair below the seat of said chair and pivoted at their rearward ends to 35 a pivoted chair back; guides engaging the forward ends of the bars and provided with fixed detents engaging teeth of said bars to normally prevent longitudinal movement of the bars and seat back in one direction; a shaft mounted transversely of the chair adjacent the forward ends of the bars; actuating members secured upon the shaft and provided with arms movable to engage the forward ends of the bars to move the same out 40 of engagement with the detents; and a hand lever rigidly connected to the shaft and extending upwardly at one side of the chair to be grasped and manually operated by a person seated in the chair in normal sitting 45 position to move the toothed bars simultaneously out of engagement with their respective detents.
- In witness whereof, I hereunto set my signature.
- CHARLES E. FERREIRA.
